UNITED STATES PATENT OFFICE

FRANK A. TITTEMORE, OF RICHMOND, CALIFORNIA, ASSIGNOR TO HOPKINS SPRAY EQUIPMENT COMPANY, OF SAN FRANCISCO, CALIFORNIA, A CORPORATION OF NEVADA

SPRAY GUN

Application filed June 4, 1927. Serial No. 196,483.

This invention relates to spray guns, and particularly to devices of this nature employed in spraying or applying liquid paints, lacquers, varnishes and the like upon surfaces.

5 The object of the invention is to provide a spray gun which is simple in structure, economical to manufacture, and efficient in use.

A further object is to provide a spray gun of the character referred to wherein the nature, shape or dimensions of the spray delivered may be controlled, altered or varied as may be desired or required according to the nature or character of the material or of the surface to be sprayed, or other condition 10 encountered in the use of the device.

A further object is to provide a spray gun of the character referred to wherein the parts are few and simple, and easy to assemble, remove, replace or repair.

20 Other objects of the invention will appear more fully hereinafter.

The invention consists substantially in the construction, combination, location and relative arrangement of parts, all as will be more fully hereinafter set forth, as illustrated in the accompanying drawing, and finally pointed out in the appended claims.

In the accompanying drawing:—

30 Fig. 1 is a view in vertical longitudinal central section of a structure of spray gun embodying the principles of my invention.

Fig. 2 is a broken detail view in perspective of the nozzle end of the gun.

35 Fig. 3 is a view in elevation of the outer end of the same.

Fig. 4 is a broken detail view in longitudinal section of the spray disk showing the seating of the same upon the cone-shaped or tapering end of the tube through which the material to be sprayed is delivered, the plane of section being at right angles to that of Fig. 1.

40 Figs. 5, 6 and 7, are broken detail views in longitudinal section of the nozzle end, the plane of section containing the air slits or openings in the spray disk, and illustrating various relations and dispositions of the air slits with reference to the tip end of the material tube to control or vary the character 45 of the spray to be produced.

Figs. 8, 9 and 10, are, respectively, rear or inner end elevations of the spray disks shown in Figs. 5, 6 and 7.

Figs. 11, 12 and 13 are, respectively, illustrations in diagram of the shape or form of spray obtained with the nozzle arrangements shown in Figs. 5, 6 and 7.

Figs. 14 and 15 are views similar to Figs. 8, 9 and 10, showing slightly modified arrangements of the air slits in the spray disk, 60 and

Figs. 16 and 17 are diagrammatic illustrations of the forms of sprays obtained with the spray disks shown in Figs. 14 and 15, respectively.

The same part is designated by the same reference numeral wherever it occurs throughout the several views.

In the use of spraying equipments of various sorts and for various purposes it is a common expedient to employ spray guns, nozzles, air brushes or the like which, generally, include a tubular member through which the material to be sprayed is delivered and a head or spray member having an orifice which encircles the tip end of the material supply tube or member, and through which air under pressure is delivered. This air jet, encompassing and surrounding the tip of the material tube, is designed and intended to exert a siphonic action on material to be sprayed, tending to draw it through its delivery tube, and also to exert an atomizing action upon the material and to project the atomized particles of material onto the surface to be painted or sprayed. It has been found, however, in modern practice, in the use of spraying devices of this nature, that the envelope of air which thus is projected forwardly in the direction of the length of the material tube, and which encircles the stream of material, often fails to effect the desired atomization of the material, as it comes in contact with only the peripheral surface of the material stream, with the result that the material is not properly broken up or atomized. Moreover, the resulting spray is of more or less cylindrical form with the bulk of the unatomized material constituting the central portion or core thereof,

65

75

95

100

and hence not only is there great waste and loss of material due to failure to secure proper atomization thereof, but there is likewise failure to secure proper application thereof to the surface to be sprayed. To overcome these objections, and they are serious ones, it has been proposed to employ auxiliary or additional air jets through the nozzle to supplement the material encircling siphonic and atomizing jet, the auxiliary or additional jets being directed across the line of projection of the atomized, or partially atomized, material at a point forwardly of the delivery end of the material tube. The principal purpose of such auxiliary or additional jets is to form the spray into fan shape in order to increase the efficiency, and to reduce the time required to effect, the spraying operation. The addition of the auxiliary transverse jets, however, does not correct the faults of the central encircling jet. They tend to split the tubular jet into halves thereby forming a central zone in the spray which is more or less devoid of material which is objectionable. Hence, the spray nozzles at present most commonly in use, even with the auxiliary jets, remain inefficient and wasteful of material as well as of time and fail to secure desirable results, besides necessitating the use of large volumes of air which increases the power requirements and hence its cost. Moreover, by reason of these additional jets meeting or intersecting each other at a point forward of the extremity of the tip, a back eddy effect is created which causes particles of the sprayed material to deposit upon the end surface of the tip thereby clogging the orifice therethrough of the main air jet and hence impairing if not destroying the spraying action of the gun, and, in any case, causing repeated interruptions of the use of the gun to enable the tip surface to be cleaned off, and the clogging material to be removed. Again, different kinds and natures of material to be sprayed and surfaces to be sprayed and other conditions encountered in use require different forms or shapes of sprays to obtain the greatest efficiency and economy. It is among the special purposes of my present invention to provide a spraying gun, air brush, or the like, which obviates these and other defects and secures economy and efficiency. To accomplish this I provide a nozzle structure in which the same jet or jets of air which exert the siphonic action on the material also atomizes the material, and projects the atomized material onto the surface to be sprayed, while at the same time said jet or jets are also utilized to shape the spray into the desired fan shape thus entirely eliminating the central encircling air jet heretofore employed. I also propose to provide a nozzle structure of the nature referred to herein whereby by simply removing and replacing a single part, namely, the spray disk;

the gun or air brush is made adaptable to producing any desired shape or dimension of spray that may be required, thus not only securing efficiency but also economy of material, time and cost in effecting the spraying operation. 70

Generally speaking, the advantages of my invention are realized by providing a gun or air brush nozzle structure in which is adapted to be received readily removable and replaceable spray disks each having air ducts or slits formed therein of the required or desired arrangement, structure, dimensions or relation, to produce its own particular dimension, character, shape or form of spray, the air jets delivered through such ducts or slits accomplishing not only the siphonic and atomizing actions, above referred to, but also the shaping of the spray. In carrying out my invention I eliminate entirely the encircling air jet, that is, a jet which envelops and encircles the material, and, instead, employ slits or ducts in the spray disk which extend alongside of and in the direction of the length of, the end of the material tube, 80 but preferably inclined toward the same. I have also found that the best results are secured when the whole or the greater part of the air of the jets delivered through said ducts or slits strike at an angle the exterior surface of the material tube at or near the tip end of the latter, and that by bringing the points where the inclined jets encounter the exterior surface of the material tube tip closer to, or removing the same back farther 90 from the extremity of said tip, I am enabled to secure a very desirable, important and valuable control of the shape of the spray produced. Therefore by providing spray disks having relatively varying shapes, forms, dispositions, or other characteristics, of air ducts or slits, capable of being readily and easily assembled, removed and replaced, with reference to the material tube and its tip, I am enabled, with the same gun, to secure any 100 desired shape or characteristic of spray, while at the same time securing a maximum of efficiency and economy in effecting the spraying operations. I am also enabled to economize to the extent of from forty to fifty 110 per cent in the volume of air required, which means a very great saving in cost of structure and operation of the power equipment. This economy is secured by eliminating the central encircling air jet orifice heretofore used, and which required a large volume of air for operation and using only the air delivered through the ducts or slits to accomplish not only the siphonic action but also the atomization and projection of the paint material, as well as the shaping of the spray 120 itself, as will be more fully explained herein after. 125

While I have shown and will now describe a structure of spray gun, air brush, or the 130

like, and various forms of spray disks for use therewith, as embodiments of my invention, it is to be understood that my invention is not to be confined or limited to the exact details of structure which I have selected as illustrative of the principles of my invention. And while I have shown my invention as applied to spray guns for paint, lacquer or varnish application, I am not to be limited with respect to the nature or character of the material to be sprayed nor to the purpose to which the structure is to be put as a spraying device.

Referring to the drawing, numeral 20 designates the body of the gun which is provided with a handle or grip 21. At its forward end the gun body is formed with a chamber 22, to which the material to be sprayed is delivered through suitable hose or other connection (not shown) with a nipple 23. Removably fitted into the forward end of chamber 22, is a plug 24, having a central hole or passage 25 therethrough, which opens at its inner end into the material chamber. The forward end portion of the plug 24 is exteriorly coned, as shown at 27, and its extreme forward end terminates in an annular tip 26. The inner end portion of the plug 24 seats tightly against a cone seat formed in the end surface of the gun body surrounding the bore of chamber 22 in which the inner end of the plug is received. Adapted to be tightly but removably seated upon the coned surface 27 of plug 24 is a member 28 which I will call the spray disk. This member is in the form of an annular fitting having its inner surface or face formed into a bearing to seat air tight against the exterior cone surface 27 of plug 24. A central opening is formed in the spray disk 28 through which extends the tip 26 of plug 24, the spray disk fitting thereon tight but removable. The spray disk 28 is preferably formed with diametrically disposed lugs or extensions 29, at its outer face to afford protection against mechanical injury to the tip 26. The central opening or bore through the spray disk member 28 is formed at diametrically opposite points with thin narrow slits 30, so that when said spray disk is assembled in place on the outer end of the plug 24, and seated against said plug, said slits extend alongside the exterior surface of the plug 24, but inclined outwardly towards the exterior surface of the tip 26, and constitute air ducts or passages. The disk 28 when seated upon the outer end of the plug 24 is off-set forwardly from the end of the gun body so as to form an annular air chamber 31, and the ducts 30 lead forwardly from said annular air chamber on lines which converge inwardly towards and deliver upon the exterior surface of the tip 26. Upon striking the exterior surface of the tip the air jets travel along said surface and on past the extremity of the tip. This exerts a wiping action upon the tip which keeps the surface thereof clean and free from any accumulations of material deposited thereon and avoids any clogging that might otherwise result from any such deposits. This arrangement also prevents the creation of any back eddies of the paint material thereby avoiding any tendency of the material to deposit on the tip. These ducts or slits constitute the only line of passage of compressed air through the spray head of the gun from the air chamber to the tip, and consequently all the air required in the use of the gun for atomizing, siphoning, spraying, and shaping the spray is delivered through said ducts or slits. The point at which these ducts deliver their air jets upon the exterior surface of the tip plays a vitally important part in shaping the spray. The farther towards the rear these jets are delivered upon the tip 26, the thicker will be the body of the issuing spray at its central portion and the thinner its side edges, and if portions of the air jets pass forwardly of the extremity of the tip without striking the exterior surface of the tip the action is to cause a spray which is more or less thin at its central portion while its side edges are more or less thicker, and, in some cases, the spray is actually divided or split along its center line into two halves. The desirable and most efficient operation is secured when the spray is thin and of uniform thickness throughout its entire width as shown in Fig. 12. This result is secured by so disposing the ducts or slits as to enable the air jets delivered therethrough to impinge upon the tip at a point as close to the forward extremity of the tip as possible without actually escaping it. Should the entire jets pass by the forward end of the tip 26 without striking the exterior surface thereof, the entire spraying action is destroyed and the device would be useless, where the same jets are relied on to secure the siphoning and atomizing actions as well as the spray shaping action. Thus, in Figs. 5 and 8 I have shown a spray disk 28 wherein the air ducts formed by two narrow slits 30 of V-shape in cross section are formed in the tapering bore of the spray disk 28, and are disposed at diametrically opposite sides of the plug 24, said slits being of the same shape, depth, length and width, and delivering upon the exterior surface of the tip at a point removed inwardly from the extremity thereof. In Fig. 11 I have diagrammatically illustrated at 32 the contour of the spray resulting from this arrangement. In Figs. 6 and 9 I have shown a similar arrangement of ducts 30, except that in this instance they are so disposed with relation to the extremity of the tip 26, that the air from the ducts strikes the surface of the tip closer to its extremity, thereby producing a thin flattened

or narrow spray of uniform thickness, as illustrated at 33 in Fig. 12.

Other variations in the shape or form of the spray may be produced by other variations in the nature, character, shape or arrangement of the slits or ducts 30. Thus, in Figs. 7 and 10 I have shown one of a pair of diametrically disposed slits as being thin, narrow and of a shallow depth and the other 10 broad and deep, and both delivering against the exterior surface of the tip 26 rearwardly of its extremity. The resulting spray, as indicated at 34, Fig. 13 is of arc-shape. By employing two pairs of slits of equal dimensions and symmetrically arranged in the bore surface of the spray disk, as shown in Fig. 14, a more or less square shape of spray, indicated at 35 Fig. 16 is produced when the air jets strike the outer surface of the tip. A 15 similar arrangement is shown in Fig. 15 except the members of one pair of the slits are narrow and shallow and those of the other pair are broad and deep. This results in a more or less rectangular form of spray as indicated at 36, in Fig. 17, when the air jets encounter the tip.

Thus it will be seen that by providing a set of spray disks each having its own particular form and arrangement of slits 30, to 20 produce its own distinctive type of spray, but all of said disks constructed alike with reference to the assembly thereof with the nozzle member or plug 24, and gun body, I am enable to use the same gun to produce 25 any desired type of spray by merely detachably assembling the proper spray disk with said plug and gun. Many different ways will occur to those skilled in the art to detachably and removably assemble and mount the 30 spray disks. I have shown one simple and efficient form of connection for this purpose which is illustrative of the principle involved, wherein the spray disk 28 is formed with an annular peripheral shoulder 37, arranged to be engaged by an inwardly extending flange 38 at the outer end of a coupling sleeve 39 which is threaded upon the end of the gun body. By inserting a spray disk 28 in the coupling sleeve with the flange 38 of the latter engaging against the shoulder 37, and then screwing up the sleeve on the end of the gun barrel or body, the spray disk is caused to be clamped tightly in its seating on the plug 24, and is thereby centered thereon, with the tip end 26 of the plug fitting 45 tightly through the central orifice or portion of the bore through the spray disk. To replace a spray disk by another for obtaining a different character of spray it is only necessary to uncouple the sleeve 39 from the end of the gun body, remove the one spray disk from the sleeve and slip into place therein another having the required structure or arrangement of air slots and screw up the sleeve 50 on the gun body. The spray disks can be

made very cheaply and quickly and carried in sets for each gun.

The air supply into and through the slits 30, or into the chamber 31 with which said slits communicate, may be accomplished in 70 any desired way and under any desired system of control. As one illustrative arrangement for accomplishing this purpose I have shown the handle end of the gun body formed with a chamber 40 which is in communication with chamber 31 at the front end of said body, as, for example, through the passage 41. Air under the desired regulation of pressure thereof, or otherwise, is delivered into the chamber 40 from any convenient 75 source, as, for example, through a hose, or other form of connection (not shown) attached to a nipple 42 and pipe section 43 in the handle or grip 21, or such connection may be made through a plug of suitable structure 80 fitted into the rear end of the chamber 40. The communication between chamber 40 and passage 41 may be controlled in any suitable way, as, for instance, by means of a valve 44, normally maintained seated, as by a spring 85 45, but capable of being unseated by means of a finger piece or trigger 46 arranged to engage the stem 47 of said valve. In like manner the material to be sprayed may be delivered into chamber 22, under any desired 90 system of pressure or other control, and the supply thereof through the plug 24 and nipple 26 controlled in any suitable or desired manner, such for example, as by means of the usual needle valve 48, which extends into 95 the tip 26, said valve being normally maintained in closed or cut-off position by means of a spring 49, acting upon the stem 50 of said valve. The needle valve 49 may also be unseated or shifted to open the tip 26, by 100 the manipulation of the finger piece or trigger 46. The properly timed operations of 105 the valves 44 and 48 may be effected in any desired manner, as, for instance through the coupling 51 of the stems 47 and 50, of said 110 valves. However, all these details of air and material supply and control, in and of themselves, form no part of my present invention, and hence may be varied throughout a wide 115 range, without affecting the functioning and operation of the nozzle structure wherein my present invention more particularly resides. The control of the material supply to the action of the spray shaping jets, effected 120 through the operation of needle valve 48, 125 may be adjusted in various ways. I have shown a simple arrangement wherein the stem 47 abuts against the end of an adjustable screw plug 53, mounted at the rear end of the gun body. By turning up or backing off this screw plug the range of longitudinal movement of said stem 47 is varied, thereby varying the range of movement of the needle valve 48, and its stem 50. To indicate the 130 position of the adjustment of the abutment

53, and to thereby enable said abutment to be restored to any desired position after having displaced therefrom for any special reason, I associate with said abutment a hand or 5 pointer 54, which cooperates with an annular graduated scale or row of serrations, or other suitable indices 55, provided at the rear end of the gun body. The alignment throughout of the valve stems 50 and 47, the operating coupling 51 between them, and the adjustable stop device 53, with its associated and cooperating hand or pointer makes an exceedingly simple structure which is efficient and very economical to manufacture.

15 From the foregoing description it will be seen that I provide an exceedingly simple efficient and inexpensive structure of spray gun or air brush wherein I employ inclined air jets not only to exert a siphonic action on 20 the material to be sprayed, and to effect the atomization and application of the atomized material, but which also produces the desired shape and contour of spray to avoid waste of material and loss of time in accomplishing 25 the application of the material. In the use of a spray gun embodying my invention I am enabled to secure a very large economy and saving of both material and time in the application, besides effecting a more perfect 30 and satisfactory application, of the material and at largely reduced power cost, due to the saving of air volume required. I am also enabled to employ the gun where high pressure of atomizing air is the only pressure available 35 for use with the apparatus because by striking the surface of the material tube tip before striking the material and the pressure is caused to be reduced and hence excessive atomization is prevented.

40 Having now set forth the objects and nature of my invention, and a structure embodying the principles thereof, what I claim as new and useful, and of my own invention, and desire to secure by Letters Patent, is:—

45 1. A spray gun provided with material and air passages, respectively, and control means therefor, said material passage terminating in a delivery tip, and a spray disk having a central bore to receive said tip therethrough, 50 said bore having thin narrow slits formed in the inner surface thereof, said slits disposed at opposite sides of said material passage and communicating with the air passage, and delivering upon said tip adjacent the extremity 55 thereof, said slits affording passages for air jets to siphon the material through the tip and atomize and project the same and shape the projected spray.

60 2. A spray gun provided with material and air passages and control means therefor, said material passage having an exterior seating surface and a delivery tip, a spray disk constructed to fit against said seating surface and having an opening through which said tip 65 protrudes, said disk also having slits disposed

at opposite sides of said material passage communicating with the air passage, and delivering upon the exterior surface of the protruding part of said tip adjacent the extremity thereof, and means to detachably 70 secure said disk in tight seating engagement with said seating surface.

3. A spray gun having material and air passages and means to control the same and combined material siphoning, atomizing, 75 spraying and spray shaping means including narrow slits elongated in cross section communicating with the air passage and disposed at opposite sides and delivering upon the exterior surface of the material passage adjacent its delivery extremity, the transverse widths of said slits disposed at right angles to the opposed exterior surface of the material passage.

4. A spray gun having material and air 80 passages, and means to control the same, said material passage including a plug having an exterior seating surface and a delivery tip extension, a spray disk mounted on said seating surface and having a bore through which 85 said tip extension protrudes, said bore having narrowed slits elongated in cross section formed at diametrically opposite points therein, said slits having their width dimension extending radially with respect to the 90 opposed surface of said plug communicating with the air passage and inclined forwardly towards and delivering upon the exterior surface of said tip extension, adjacent the extremity thereof, and means to detachably 95 secure said spray disk upon said seating surface.

5. A spray gun having controlled material and air passages, said material passage including a plug secured in the forward end of the gun, and having an exterior seating 100 surface and a tip extension, a spray disk mounted on said seating surface and having a central opening to receive said tip extension, said central opening having narrowed slits 105 elongated in cross section in the surface thereof inclined forwardly towards and delivering upon the exterior surface of said tip extension adjacent the delivery terminal thereof, said slits communicating at their rear ends with the air passage, and means 110 connected to the end of the gun and engaging said spray disk to detachably secure and retain the same seated upon said seating surface.

6. A spray gun having material and air 115 passages, and means to control the same, said material passage including a plug secured in the forward end of the gun, and having an exterior seating surface and a tip extension, a spray disk adapted to be removably centered and seated upon said seating surface and having a central opening to receive said tip extension said disk having an annular peripheral shoulder, said central opening having narrowed slits elongated in cross sec- 120 125 130

tion formed in the surface thereof, said slits extending forwardly and inclined inwardly towards and delivering upon the exterior surface of the terminal end of said tip, said slits 5 also communicating with said air passage, and a sleeve detachably engaging the end of the gun and having an annular flange to engage the shoulder on said disk to detachably clamp the latter into its seating upon said 10 seating surface.

7. A spray gun provided with material and air passages respectively, and control means therefor, said material passage including a plug having inclined exterior surface and a 15 terminal portion and a central bore through which the material is delivered and a spray disk detachably and removably mountable upon the said plug and seating against the exterior inclined surface thereof, said disk having a central bore therethrough to receive the plug terminal tip, the seating surface of said disk having diametrically disposed narrowed slits elongated in cross section the longer dimension thereof being in radial relation to said seating surface, said slits communicating with the air passage and delivering upon said tip extension adjacent the extremity thereof.

8. A spray gun having a spray head including a fluid tip having a central bore therethrough for the delivery of the material to be sprayed, a spray disk having a bore therethrough to receive and seat tightly upon the exterior surface of the tip, the delivery extremity of the tip extending through and beyond said spray disk, said spray disk having ducts or passages in the bore surface thereof for the delivery therethrough of air jets for siphoning the material through the 35 tip bore, and atomizing and projecting the same and shaping the projected spray, the ducts or passages of the spray disk delivering upon the annular surface of said tip at a point near the extremity thereof.

45 In witness whereof I have hereunto set my hand this 11th day of May, 1927.

FRANK A. TITTEMORE.
